Patented Feb. 9, 1915.

UNITED STATES PATENT OFFICE.

FRANK FEYRER, OF WESTHOFF, TEXAS.

COMBINATION-PENKNIFE.

1,127,609.

Specification of Letters Patent.

Patented Feb. 9, 1915.

Application filed April 13, 1912. Serial No. 690,632.

To all whom it may concern:

Be it known that I, FRANK FEYRER, a citizen of the United States, residing at Westhoff, in the county of Dewitt and State 5 of Texas, have invented a new and useful Combination-Penknife; and I do hereby declare the following to be a full, clear, and exact description of the invention, such as will enable others skilled in the art to which 10 it appertains to make and use the same.

This invention relates to a new and useful combination pen-knife.

It is the principal object of this invention to provide a pen-knife of this nature having 15 several instruments or tools, such as cutting blades, an awl, a tack puller, a screw driver, a beer-bottle opener, a cork screw or extractor, and a thorn extractor.

Another object of the invention is to provide 20 one of the cutting blades with a pocket, and pivot the cork screw to said blade, so as to be received in the pocket when closed.

Another object is to provide another cutting blade with a pocket, to receive the awl, 25 which is pivoted to said blade.

The invention comprises further features and combination of parts, as hereinafter set forth, shown in the drawings and claimed.

In the drawings:—Figure 1 is a view of 30 the pen-knife, constructed in accordance with the invention, showing the cutting blades and the other instruments closed within the handle. Fig. 2 is a view of the pen-knife showing the cutting blades and 35 the other instruments open, showing the back springs partly in elevation and dotted lines, parts being broken away. Fig. 3 is a detail view of one of the cutting blades including the cork screw, the screw driver, 40 and the beer-bottle opener. Fig. 4 is a detail view of another cutting blade, showing the awl pivoted thereto, and having at one end a tack puller. Fig. 5 is a detail view showing the forks 18 and 19 in position to 45 remove a beer-bottle cap.

Referring to the drawings 1 designates the handle of the combination pen-knife, which is provided with the usual back springs 2 and 3, which tend to hold the cutting blades 4, 5 and 6 in opened or closed position. The back spring 3 also holds a member or blade 7 in open or closed positions. This member or blade 7 comprises two arms 8, the outer ends of which terminate in curved portions 9. When the arms 8 are brought together, the curved por-

tions 9 constitute means for extracting a thorn, splinter, hair, or for removing a fish bone or the like from a person's throat, or for any other similar purpose. The handle 50 1 and the cutting blade 6 are provided with graduations 10 and 11 of inches from 1 to 6 inclusive, and fractions thereof. The cutting blade 4 is provided with a cutting edge 12, and terminates in a tack extractor 13. 55 This blade 4 is provided with a pocket 14. Pivoted at 15 to the blade 4, so as to swing laterally thereto is an awl 16. When the awl 16 is closed, it is snugly received in the pocket 14. When it is desired to use the 70 awl, the blade 4 is fully opened, then the awl is thrown laterally thereto, in which position, as shown in Fig. 4 the same may be readily utilized. The blade 5 is provided with a cutting edge 17, and terminates in 75 short and long projections or forks 18 and 19. These forks when used in conjunction with one another constitute means for removing the cap from a beer bottle. The extreme portion 20 of the fork 19, when inserted in the groove of a screw constitutes the screw driver. The manner of utilizing the forks 18 and 19 as a beer-bottle opener is illustrated in Fig. 5. The blade 5 is provided with a pocket 21. Pivoted at 22 so 80 as to swing laterally of the blade 5 is a cork screw 23. This cork screw closes within the pocket 21 when out of use. To use the cork screw, the blade 5 is fully opened, then the cork screw is thrown laterally thereto, as 85 shown in Fig. 3.

The handle may be covered on each side with pearl, bone, or any other suitable material of any desired configuration. The handle may be made of any desired shape, 90 and the graduations thereon may be cut in the handle, or marked thereon in any suitable manner, such as by painting or lithographing or otherwise.

Where either one of the tools 16 and 23 is 100 pivoted, the end wall or shoulder of the recess or pocket 14 acts as means to limit the tool when swung laterally to an open position, and when said tool is swung to such an open position, the blade may be partially closed, causing the tool to contact with one side of the handle, thereby assisting in preventing the tool from accidentally closing while being used. Moreover, when the blade (in the recess of which the tool is 105 pivoted and designed to be swung laterally to an open position) is closed partially, the

cutting edge of the blade is prevented from contacting with one's hand, while using the tool. In this case the broad combination of pivoting another tool to a knife blade is not claimed, nor is desired, but as will be observed the device embodies the specific provision of an elongated recess having a bottom wall, with a tool pivoted in one end thereof, the end wall of the recess acting to limit the tool when swung laterally to an opening position, and the knife blade being designed to be partially closed to prevent the tool from collapsing, as well as preventing the cutting edge of the blade from contacting with one hand when gripped, as specifically and definitely defined in the appended claim.

From the foregoing it will be noted there has been produced a novel, efficient and simple combination pen-knife, and one which has been found practical as a pocket article.

The arms 8 are provided with filing surfaces 24, and one of the arms is provided with a cutting edge 25.

The invention having been set forth, what is claimed as new and useful is:—

The combination with a handle having spaced sides; of a blade having a lateral recess therein and pivoted to said handle to swing into and out of the space between said sides, and a tool pivoted to said blade to swing laterally into and out of said recess, said recess being provided with a bottom wall and positioned in the blade to be entirely covered by the handle when the blade is closed whereby to entirely cover and lock said tool from movement out of said recess, whereby said blade, when the tool is swung laterally to an open position, may be partially closed, causing the tool to contact with the side of the handle.

In testimony whereof I have signed my name to this specification in the presence of two subscribing witnesses.

FRANK FEYRER.
